Patented July 10, 1928.

UNITED STATES PATENT OFFICE.

FREDERICK C. MEACHAM, OF GARDEN CITY, NEW YORK.

DEVICE FOR CALCULATING TIME.

Application filed November 13, 1925. Serial No. 68,815.

My invention relates to a device for use in the calculation of time by means of the position of certain stars; this is accomplished by reading, on my device, the relative position 5 of the stars, followed by certain calculations, as will be hereinafter fully set forth. The object of my invention is to enable the quick and easy determination of such relative position with a reasonable degree of accuracy under the conditions in which the 10 device is ordinarily used; another object of my invention is to provide a device for such purpose which shall be compact and reasonably simple and cheap to manufacture in 15 quantity.

This application is to obtain a patent on certain features of my invention other than those described and claimed in my Patent No. 1,620,980, issued March 15, 1927, on my 20 application therefor, filed April 27, 1926, for a patent on a similar device.

The accompanying drawing is a plan view of a preferred form of my device and the drawing also shows a method of using the 25 device.

In the drawing, 21 represents a disk which may be of transparent material, such as celluloid. The disk is preferably divided into four equal sectors by the perpendicular 30 diameters 25, 26. The periphery of the disk is also divided into twelve equal spaces by the diameters and the lines indicated at 22 or by other suitable means for indicating the 35 divisions of the disk; these spaces are again preferably divided, as by the lines 23, 24, into four equal parts. The lines 22, as well as the outer extremities of the two diameters, may be numbered, as indicated at 27, in the same manner as the dial of a clock, from 40 "1" to "12" inclusive. At the outer end of one diameter, adjacent the numeral "12", I prefer to place an outwardly-pointing arrow-head, or other easily noticeable mark 45 28, to indicate clearly the uppermost point of the disk.

In my preferred form, a central aperture is stamped out of the material of the disk and a small metal eyelet 29 inserted therein. Carried by the eyelet 29 is an arm 30 which 50 may be transparent. The arm, when extended, projects beyond the outer edge of the disk. The eyelet is riveted over a portion of the arm to hold it in rotatable relation to the disk. The eyelet 29 is preferably a true eyelet—i. e., of such character that it will not 55 obstruct clear vision through the aperture

at the center of the disk. The arm 30 has preferably a length about equal to the diameter of the disk and it may be slotted throughout approximately half of its length, 60 as indicated at 31, so that, when the device is not in use, the arm may slide along the eyelet over the face of the disk into position where it does not project beyond the edge of the disk. It will be understood that this 65 is merely for compactness and convenience in carrying. The longitudinal center of the arm is defined, as by the line 32, which preferably extends from the outer end of the arm to a point which (when the arm is fully ex- 70 tended) meets or crosses the edge of the disk. It will of course be understood that any other suitable means may be used to define, by means of the arm, a radial line; for example, the outer end of the arm may be 75 offset so that one edge thereof lies along a radius (extended) of the disk.

I will now describe one method of using my device; this method enables a surprisingly accurate calculation of time, at least 80 when used at or near a line of longitude which determines the standard time for that locality. Of course, when my device is used at some distance east or west of such line of longitude, the calculated time will not agree 85 so well with the standard time, but it will everywhere agree very closely with the true time or sun-time.

In the method here described, my device is used to determine the relative position of 90 the North Star or Polaris and the two stars in the constellation Ursa Major known as α and β or the "Pointers". My device is held before the eyes of the observer—say eight inches from the eyes—with the arrow-head 28 pointing upward and the diameter 25 lying in a vertical plane through the meridian. The presence of the two diameters on the face of the disk assists the observer 95 in properly positioning it. The disk should be held so as to lie in a plane perpendicular 100 to the line of vision between the observer and Polaris. The arm 30 having been fully extended, the device is then so positioned that Polaris is visible through the hole at 105 the center of the disk—as indicated at 33 in the drawing. The arm 30 is then rotated, without disturbing the position of the disk, until the "Pointers" of the constellation Ursa Major, indicated at 34, 35, lie along 110 the line 32 or the line 32 if continued. This adjustment having been made, the relative

position of the stars is read by taking the reading on the disk as determined by the position of the line 32.

Suppose, for example, the reading is, as indicated in the drawing, approximately $1\frac{1}{2}$; suppose also that the reading is taken on August 8 in any year. Then to determine the time, the following calculations are made; start with the reading—in this case, $1\frac{1}{2}$; add to that the number of months and quarter-months that have elapsed during the calendar year—in this case $7\frac{1}{4}$ (January to July, inclusive, being 7 and the eight days of August being approximately one quarter); the sum then equals $8\frac{3}{4}$; next, double this sum—giving, in this case, $17\frac{1}{2}$; subtract this final amount from $40\frac{1}{4}$ —giving $22\frac{3}{4}$. This last figure gives the time. Where, as here, the time given is greater than 12, then 12 or 24 or 36, may be deducted so that the net result will be less than 12. Proceeding thus in the example given, 12 is deducted from $22\frac{3}{4}$, leaving $10\frac{3}{4}$ —which means that the time is 10:45.

I am aware that modifications may be made in my device by those skilled in the art and, therefore, I desire protection for all such forms of my device as come within the scope of the appended claims.

I claim:

1. A stellar time indicator comprising a disk having a central opening and a marginal scale, a longitudinally slotted arm adapted to be positioned to lie wholly within the margin of said disk, means associated with said central opening having an opening in alignment therewith, said slotted arm

being rotatably and slidably carried by said means and having a line thereon which, if projected, would intersect the center of said disk.

2. A stellar time indicator comprising a disk having a central opening and a marginal scale, a longitudinally slotted arm of transparent material adapted to be positioned to lie wholly within the margin of said disk, means associated with said central opening having an opening in alignment therewith, said slotted arm being rotatably and slidably carried by said means and having a line thereon which, if projected, would intersect the center of said disk, said disk having a diametral line thereon adapted to be pointed toward the zenith when an observation is to be made.

3. A stellar time indicator comprising a disk having a central opening and a marginal scale, a longitudinally slotted arm of transparent material, an eyelet passed through said central opening and through the slot in said arm, said slotted arm being rotatably and slidably carried by said eyelet and having a line thereon, which, if projected, would intersect the center of said disk, said arm having substantially the length of the diameter of said disk and the slot therein being substantially equal in length to the radius of said disk whereby said arm may be positioned to lie wholly within the margin of said disk, said disk having a diametral line thereon adapted to be pointed toward the zenith when an observation is to be made.

FREDERICK C. MEACHAM.
